COMPARATIVE DATA FILE

Jesse M. Jones, North Hollywood, Calif., assignor
to Charles R. Hadley Company, Los Angeles,
Calif., a corporation of California

Application July 16, 1946, Serial No. 683,931

6 Claims. (Cl. 129—16.5)

1

This invention relates to a comparative data file and is directed toward the general type of file shown in the Jones et al. Patents Nos. 2,295,951 and 2,295,952 and relates to improvements over the structure shown therein.

The primary object of this invention is to provide superposed data sheets which are each individually attached for limited transverse sliding movement with relation to adjacent sheets, and each of said sheets being provided with a secondary data sheet arranged for limited transverse sliding movement relative thereto.

Another object is to provide a series of superposed data sheets, each having thereon columns for the entry of data, which sheets are connected by means permitting transverse sliding movement of the sheet to an echelon arrangement for comparison of data on the various sheets, together with a secondary sheet associated with each of the said data sheets which is attached thereto in a manner permitting relative transverse sliding movement.

These objects are to be considered in relation to the problem of providing a comparative files of data sheets which contain entries made over a period of time and in which it may be desired to compare entries of sales, for example, with corresponding entries of cost of sales and gross profit period. Thus, a series of data sheets, as shown in Patent No. 2,295,951, may be provided for showing monthly comparisons of amounts of sales, but in order to compare additional items such as gross profits, cost of sales, and so forth, additional columns would be required on each of the sheets. The individual sheets would therefore be necessarily greater in width and this is a particularly undesirable feature since the cumulative effect of the increased width of each sheet is to make the overall width of the sheet when extended unnecessarily large and space consuming. Moreover, it may be that the additional items, such as gross profits and cost of sales are only important for comparison with the particular corresponding entry of data on a particular data sheet, and are not important for comparison with other entries of gross profits and cost of sales to be carried on the other data sheets.

The present invention which contemplates the use of a secondary data sheet slidably attached to each of the echelon forming data sheet enables me to retain the desirable feature of narrowness of the data sheet, while providing additional information instantly available for comparison by merely sliding the secondary sheet transversely in either direction for comparison with the data

2

obtained on the primary sheet to which it is attached.

Other objects and advantages will appear hereinafter.

5 In the drawings:

Figure 1 is a plan view of a comparative data file embodying my invention, the various sheets thereof being shown in compact superposed relationship.

10 Figure 2 is a diagrammatical illustration showing an end view of the device with spacing between adjacent sheets exaggerated for clarity of illustration.

Figure 3 is a partial plan view showing the primary sheets extended in echelon arrangement.

15 Figure 4 is an enlarged plan view partly broken away and showing a preferred form of an engagement provided for each pair of primary and secondary data sheets.

20 Figure 5 is a view similar to Figure 4, but showing the secondary sheet extended on the opposite side from that shown in Figure 4.

Figure 6 is a sectional elevation on an enlarged scale taken substantially on the line 6—6 as shown in Figure 1.

25 Figure 7 is a sectional elevation on an enlarged scale taken substantially on the line 7—7 as shown in Figure 1.

Figure 8 is a plan view of one of the metallic staves employed in the attachment means embodied in my invention.

30 Referring to the drawings, a plurality of superposed primary data sheets 10, 11, 12 et seq. are arranged in a folder 13. These primary data sheets are substantially duplicates and each is provided with an extension 14, 15, 16 at the upper end thereof. Means of the general type shown in Patent No. 2,295,951 are provided for connecting primary data sheets together and for permitting relative sliding movement between adjacent sheets. As shown in the drawings, this means includes transversely spaced apertures 17 and 18 formed in the extensions 14, 15 and 16 of each of the data sheets.

35 A stave 19 is attached at its opposite ends to the apertures 17 and 18, the stave 19 being provided with clips 20^a adapted for engagement between the apertures 17 and 18. Each of the extensions 14, 15, 16 is also provided with a pair of transversely spaced perforations 20 and 21 adapted to receive the stave of an adjacent data sheet. Thus, the extension 15 of the primary data sheet 11 is provided with apertures 20 and 21 for reception of the stave 19 attached to the extension 14 on the primary data sheet 10. The

extension 15 also carries a stave 19 which is identical to the stave 19 carried by extension 14 and which is attached in a similar fashion to apertures provided in the extension 16 of the primary data sheet 12. If the comparative file is to be used for making monthly comparisons, twelve primary data sheets may be employed, each connected to its neighbor by the stave and perforation arrangement just described. The result is that the primary data sheets 10, 11, 12 et seq. may be arranged in vertical superposed relationship, as shown in Figure 1, or may be extended to the right or left in echelon arrangement as shown in Figure 3.

Interposed between each pair of primary data sheets are secondary data sheets 22, 23, 24 et seq. which are substantially duplicates and each of which is secured to one of the primary data sheets. Thus, secondary sheet 22 is provided with perforations for reception of a stave 25 which is identical to the stave 19 shown in Figure 8. Similarly, the secondary sheet 23 is secured to primary sheet 11 by means of stave 26 and secondary sheet 24 is secured to primary sheet 12 by stave 27. The secondary sheets are not provided with extensions at their upper ends and therefore they terminate short of the upper ends of the primary sheets. This arrangement enables the primary sheets to be connected by stave elements independently of the secondary sheets.

Perforations 28 (see Figure 6) in the secondary sheets permit them to slide on the staves 25, 26, 27 et seq. so that each of the secondary sheets may be moved transversely with respect to its primary sheet to expose either the right side or the left side of the secondary sheet, as desired. Thus, in Figure 4 the secondary sheet 22 may be moved to the left of the primary sheet 10 in order to expose the left hand data column on the secondary sheet for comparison with the data entered in columns on the primary sheet.

It will be understood from the above that the arrangement of data sheets contemplated by my invention is particularly advantageous in that it enables a series of superposed primary sheets to be moved to an echelon arrangement for comparison of the data entered on any sheet with the data entered on any other sheet, and yet providing means whereby additional data relating to any one of the primary data sheets is instantly available for comparison therewith by shifting into view data columns carried on a secondary data sheet. As a specific example, the primary data sheets may carry a central column of indicia positioned between a pair of columns adapted for entry of data, as shown in Figures 4 and 5. The central column may be entitled Sales analysis, the right column may show entries of any given period and the left column may show the total of such entries to date.

Each of such primary data sheets may comprise a sales analysis record of any particular month such as, for example, April 1946. The complete series of such sheets mounted in a folder 13 may comprise a record month by month of the calendar year and hence a convenient comparison may be made between analysis of sales data for each period, or for the total period of any particular dates, by extending the primary sheets into echelon formation either to the right or to the left, as may be required. However, if during such process of comparison it is desired to inspect or compare further information, such as gross profits or cost of sales for any given period, the secondary data sheet for that period is moved

transversely of its primary data sheet to expose the information required. The secondary data sheet may be moved to the left to expose the gross profits and cost of sales columns which show entries of data for the particular period, or it may be moved to the right to expose similar columns showing the total to date for the particular period.

Having fully described my invention, it is to be understood that I do not wish to be limited to the details herein set forth, but my invention is of the full scope of the appended claims.

I claim:

1. In a file for facilitating comparisons of entries of data, the combination of a plurality of juxtaposed primary sheets having appropriately designated columns thereon for entry of data, horizontally disposed stave members located adjacent and aligning a horizontal edge of the primary sheets for effecting a horizontal sliding connection between said primary sheets, said stave members each being attached at its ends to a primary sheet and having a sliding connection with an adjacent primary sheet so as to enable them to be normally held superposed in registry with each other, and also shiftable horizontally and laterally relative to each other into an echelon arrangement, a secondary sheet carried under each of the primary sheets and having appropriately designated columns thereon for entry of data, stave means slidably connecting each secondary sheet to its respective primary sheet so that they are normally superposed with their corresponding columns in registry, and so that each secondary sheet can be shifted transversely to said columns toward either the right or left so as to expose a portion of either side of the secondary sheet.

2. In a file for facilitating comparisons of entries of data, the combination of a plurality of juxtaposed primary sheets having appropriately designated columns thereon for entry of data, horizontally disposed stave members located adjacent and aligning the horizontal edge of the primary sheets for effecting a horizontal sliding connection between said primary sheets, said stave members each being attached at its ends to a primary sheet and having a sliding connection with an adjacent primary sheet so as to enable them to be normally held superposed in registry with each other, and also shiftable horizontally and laterally relative to each other into an echelon arrangement, a secondary sheet carried under each of the primary sheets and having appropriately designated columns thereon for entry of data, stave means positioned substantially midway between the upper and lower horizontal edges of said sheets and slidably connecting each secondary sheet to its respective primary sheet so that they are normally superposed with their corresponding columns in registry, and so that each secondary sheet can be shifted transversely to said columns toward either the right or left so as to expose a portion of either side of the secondary sheet.

3. In a file for facilitating comparisons of entries of data, the combination of a plurality of juxtaposed primary sheets having appropriately designated columns thereon for entry of data, means for attaching the primary sheets together for limited transverse sliding movement, including a stave element extending transversely of each sheet near one horizontal edge thereof and secured thereto at its outer ends, transversely spaced perforations in each primary sheet

adapted to receive the stave element of an adjacent primary sheet in slidable relation, a secondary sheet carried under each of the primary sheets and having appropriately designated columns thereon for entry of data, additional transverse stave elements for slidably connecting each secondary sheet to its respective primary sheet so that they are normally superposed with their corresponding columns in registry, and so that each secondary sheet can be shifted transversely to said columns to expose a portion of either side of the secondary sheet.

4. In a file for facilitating comparisons of entries of data, the combination of a plurality of juxtaposed primary sheets having appropriately designated columns thereon for entry of data, means for attaching the primary sheets together for limited transverse sliding movement, including a stave element extending transversely of each sheet near one horizontal edge thereof and secured thereto at its outer ends, transversely spaced perforations in each primary sheet adapted to receive the stave element of an adjacent primary sheet in slidable relation, a secondary sheet carried under each of the primary sheets and having appropriately designated columns thereon for entry of data, additional transverse stave elements positioned substantially midway between the upper and lower horizontal edges of said sheets and adapted for slidably connecting each secondary sheet to its respective primary sheet so that they are normally superposed with their corresponding columns in registry, and so that each secondary sheet can be shifted transversely to said columns to expose a portion of either side of the secondary sheet.

5. In a file for facilitating comparisons of entries of data, the combination of a plurality of superposed alternate primary and secondary sheets each having appropriately designated columns thereon for entry of data, an extension on each of the primary sheets projecting beyond one end of the adjacent secondary sheets, a first stave element extending transversely across each primary sheet and secured at its outer ends to said

10

extension, transversely spaced perforations in each extension adapted to receive the stave element of an adjacent primary sheet in slidable relation, a second stave element extending transversely across and under each primary sheet and secured thereto at its outer ends, transversely spaced perforations in each secondary sheet adapted to receive the second stave element of an adjacent primary sheet in slidable relation, whereby each secondary sheet may be shifted transversely under the superposed primary sheet to expose a portion of either side of the secondary sheet.

6. In a file for facilitating comparisons of entries of data, the combination of a plurality of superposed alternate primary and secondary sheets each having appropriately designated columns thereon for entry of data, an extension on each of the primary sheets projecting beyond one end of the adjacent secondary sheets, a first stave element extending transversely across each primary sheet and secured at its outer ends to said extension, transversely spaced perforations in each extension adapted to receive the stave element of an adjacent primary sheet in slidable relation, a second stave element extending transversely across and under each primary sheet at a position substantially midway between the upper and lower horizontal edges thereof and secured thereto at its outer ends, transversely spaced perforations in each secondary sheet adapted to receive the second stave element of an adjacent primary sheet in slidable relation, whereby each secondary sheet may be shifted transversely under the superposed primary sheet to expose a portion of either side of the secondary sheet.
